(57) **CLAIM**

The ornamental design for a thermostat guard, as shown and described.

DESCRIPTION

FIG. 1 is a top, front and right side perspective view of a thermostat guard in accordance with my new design;

FIG. 2 is a front elevation view of the thermostat guard shown in FIG. 1;

FIG. 3 is a right side elevation view of the thermostat guard shown in FIG. 1;

FIG. 4 is a top plan view of the thermostat guard shown in FIG. 1, the bottom plan view being a mirror image thereof;

FIG. 5 is a left side elevation view of the thermostat guard shown in FIG. 1;

FIG. 6 is a top, front and right side perspective view of a second thermostat guard in accordance with my new design; FIG. 7 is a front elevation view of the thermostat guard shown in FIG. 6;

FIG. 8 is a right side elevation view of the thermostat guard shown in FIG. 6;

FIG. 9 is a top plan view of the thermostat guard shown in FIG. 6, the bottom plan view being a mirror image thereof; FIG. 10 is a left side elevation view of the thermostat guard shown in FIG. 6;

FIG. 11 is a top, front and right side perspective view of a third thermostat guard in accordance with my new design; FIG. 12 is a front elevation view of the thermostat guard shown in FIG. 11;

FIG. 13 is a right side elevation view of the thermostat guard shown in FIG. 11;

FIG. 14 is a top plan view of the thermostat guard shown in FIG. 11, the bottom plan view being a mirror image thereof; FIG. 15 is a left side elevation view of the thermostat guard shown in FIG. 11;

FIG. 16 is a top, front and right side perspective view of a fourth thermostat guard in accordance with my new design; FIG. 17 is a front elevation view of the thermostat guard shown in FIG. 16;

FIG. 18 is a right side elevation view of the thermostat guard shown in FIG. 16;

FIG. 19 is a top plan view of the thermostat guard shown in FIG. 16, the bottom plan view being a mirror image thereof; and,

FIG. 20 is a left side elevation view of the thermostat guard shown in FIG. 16.

The rears of the thermostat guards do not comprise any portion of the invention, and hence are not shown in the drawings.

The broken line showings are for illustrative purposes only and form no part of the claimed design.
